DISPLAY PACKAGE WITH TRANSPARENT WRAPPER

George Arlington Moore, New York, N. Y., assignor to National Biscuit Company, New York, N. Y., a corporation of New Jersey

Application February 9, 1945, Serial No. 577,078

10 Claims. (Cl. 206—45.33)

1

My invention pertains to display packages and has for its principal object to provide a package for food stuffs, such as biscuit, crackers, cookies, wafers, candies, confections, and other products, that will effectually display the contents, give good protection thereto, be attractive in appearance, strong and durable, easy to open and of low cost.

In recent years a practice has developed of packaging many food stuffs, particularly crackers, cookies and the like, in cellophane bags. Consumers in general like this style of package because they can see the kind, quality and condition of the merchandise. But they are objectionable because they give little or no protection against breakage, and crumbs that are formed within the packages make them unsightly. Also such bags are costly because of the large amount of cellophane used and because the manufacturer must enclose them in strong expensive containers to protect the articles during shipment and handling.

An object of the present invention is to provide a package that gives a better display of the merchandise than does the cellophane bag and also is strong enough to protect the contents against breakage during shipment and handling. My improved package is strong enough so that a shipping container is not required but a number of packages, as six or twelve, may be bundled for shipment.

In general my improved package includes a base or holder that is open so as to display the contents on two or three sides and provides a support on which the articles, as biscuit, cookies and the like, may be placed or stacked in orderly arrangement and tightly enclosed in a sealed transparent wrapper. A partition or deck usually is provided to give additional rigidity to the package, brace the ends, support the wrapper, prevent displacement of the contents within the package, and hold the top layer of articles closely against the wrapper for effectual display.

In the accompanying drawings, I have shown several adaptations of my invention as illustrations of both the broad and specific principles involved.

Fig. 1 shows a blank for forming a base or holder in its simplest or basic form.

Fig. 2 shows the holder formed from the blank of Fig. 1.

Figs. 3 and 4 are plan and perspective views, respectively, of a deck or partition that may be used between layers of biscuit in the package.

Fig. 5 is a perspective view of a completed

package, with the transparent wrapper broken away in part.

Fig. 6 is a section of the package of Fig. 5, taken substantially on line 6—6.

Fig. 7 is a blank for making another form of deck or partition.

Fig. 8 is a deck formed from the blank of Fig. 7.

Fig. 9 shows a completed package using the holder of Fig. 2 and the deck of Fig. 8.

Fig. 10 is a section taken substantially on line 10—10 of Fig. 9.

Fig. 11 shows a blank for making another form of deck.

Fig. 12 shows the deck made from the blank of Fig. 11.

Fig. 13 is a section of line 13—13 of Fig. 12.

Fig. 14 shows a completed package using the holder of Fig. 2 and the deck of Fig. 12.

Fig. 15 is a section of the package taken on line 15—15 of Fig. 14.

Figs. 16 and 17 are plan and perspective views of the flat part of a two piece deck.

Fig. 18 is a blank for forming a U-shaped wing member to be used with the flat member of Figs. 16 and 17.

Fig. 19 shows the wing member of Fig. 18 bent to U-shape.

Fig. 20 shows a package formed from the holder of Fig. 2 and the deck of Figs. 16 to 19.

Fig. 21 is a section substantially on the line 21—21 of Fig. 20.

Fig. 22 is a blank for a modified form of base or holder.

Fig. 23 shows the base formed from the blank of Fig. 22.

Fig. 24 is a blank for another form of deck.

Fig. 25 shows a deck formed from the blank of Fig. 24.

Fig. 26 shows a package using the holder of Fig. 23 and deck of Fig. 25.

Fig. 27 is a section taken substantially on line 27—27 of Fig. 26.

The blank of Fig. 1 is made from card board or the like and is divided by score lines 30, 31, 32, 33 into a bottom panel 34, two ends 35, 36 and two top flaps or lips 37, 38. It is folded on the score lines to make the holder or base as shown in Fig. 2. This base is used in many forms of the invention illustrated.

The separator deck and brace 39 of Figs. 3 and 4 is a rectangular piece of card board and its dimensions are the same, or substantially the same, as those of the bottom panel 34. One or 55 more of these decks may be placed between rows

or layers of the biscuit to brace the ends, impart rigidity to the package and give better protection to its contents.

A complete package is shown in Fig. 5. Three rows or layers of biscuit 40 are arranged on the bottom 34 of the holder in stacked relation, the height of the stacks being substantially equal to the height of the ends 35, 36. A deck 39 is placed between the two top layers. The lips 37, 38 are turned down over the edges of the adjacent top biscuit and the whole wrapped in a transparent wrapper 41 which is heat-sealed against the bottom of the tray and against the two ends, as shown at 42. A tear tape or rip cord 42' may be provided at one end for easy opening 15 of the package, similar to that shown in my co-pending application Ser. No. 555,162, filed September 21, 1944, now Patent No. 2,494,446, granted January 10, 1950.

The wrapper 41 is wrapped snugly about the 20 holder and biscuit. The deck 39 holds the biscuit in place, helps to keep the wrapper taut and smooth on the narrow sides, and braces the ends against inward collapse. The separator being between layers of biscuit will not flex or bend from pressure on the ends. The flaps 37 and 38, due to the resilience of the material, tend to spring up and keep the top of the wrapper smooth. The wrapper 41 being transparent, as cellophane, gives a very good display of the contents through the open sides and top of the tray. The articles, as biscuit, are wrapped tightly so that there is no tendency to slide or shift in the package nor do the edges crumble to make the package unsightly.

The deck 43 of Figs. 7 and 8 is the same size as the bottom panel 34 of the holder. It has a number of U-shaped cuts 44, 45, 46, the open ends of which are connected by score lines 47, 48, 49 to form tongues 50, 51, 52 that are bent up perpendicular to its surface. The number of tongues is one less than the stacks of biscuit on the holder. Figs. 9 and 10 show a package incorporating the deck of Fig. 8 with the holder of Fig. 2. Four stacks of biscuit 40, each containing six 45 biscuit, fill the holder. The deck 43 is placed between the two top layers with the tongues 50, 51, 52 lying between the biscuit. The height of the tongues is substantially equal to the thickness of a biscuit. This package is more rigid and stronger than the package of Fig. 5 with the plain deck 39. It is particularly adapted for use with round biscuit but not limited thereto. The tongues 50, 51, 52 prevent displacement of the top biscuit and also give additional support to the top of the transparent wrapper 41, which is heat-sealed against the bottom and ends of the holder, as at 42. In some instances the deck 43 may be placed between the second and third, or between the third and fourth, layers of biscuit. In such cases the height of the tongues 50, 51, 52 will equal the thickness of two or three biscuit, as the case may be.

In Figs. 11, 12, 13, I show another form of deck that may be used with the holder of Fig. 2. The deck is formed from a single piece blank having a rectangular panel 53 of the same size as the bottom 34 of the holder. Opposite wings 54, 55 are turned up at the sides of the panel along score lines 56, 57. U-shaped cuts 58 and scores 59 provide tongues 60 that are turned up the same as the tongues on separator 43. The height of the tongues 60 is the same as the height of wings 54, 55 and equals the height of the rows of 75

biscuit above the deck, which in the package illustrated is three, but may be one, two or more.

In the package of Figs. 16 to 21, the blank 61 is provided with slits 62, 63, 64, 65 to receive the tongues 66, 67, 68, 69 of the U-shaped divider 70. This U-shaped divider has a base 71 and two sides 72, 73 which are cut out on their top edges to form the tongues 66 to 69.

A package using a deck formed from the blank and divider of Figs. 16 to 19 and the holder of Fig. 2 is shown in Figs. 20 and 21. To form this package, the blank of Fig. 18 is folded to form the U-shaped divider of Fig. 19. The tongues 66, 67, 68, 69 are then inserted in the slots 62, 63, 64, 65 of the blank 61 to form a cellular deck that is placed in the holder with the base 71 resting on the bottom 34. This forms three lower cells or compartments, each adapted to receive a stack of biscuit, usually three or more high, and three open topped cells or spaces, each adapted to receive one or more biscuit. The height of the sides 72, 73 substantially equals the width of the end panels 35, 36, so that the tops of the tongues 66, 67, 68, 69 lie substantially in the plane of the lips 37, 38 in the finished package. The biscuit are omitted from Fig. 20, for the sake of clearness in showing the structure of the package, but Fig. 21 shows the arrangement of the biscuit in lower and upper cells or compartments. When all the cells are filled with biscuit the lips 37, 38 are turned down and the whole enclosed in a transparent wrapper 41 which is sealed at 42 and provided with the rip cord 42', the same as the other forms of my invention.

Fig. 22 shows a blank made from card board or like material of suitable grade that is scored at 80, 81, 82, 83 to provide a bottom 84, ends 85, 86, and lips 87, 88, that correspond to the same parts of Fig. 1. A score line 89 defines one edge of a back or side 90 that may be plain or have cut-outs 91, 92, 93, 94 equal to the number of stacks of biscuit through which they may be seen in the finished package. When the blank is folded along its score lines it makes a holder as shown in Fig. 23.

Any of the decks of Figs. 4, 8, 12 and 16 may be used with the holder of Fig. 23 as also may the deck 95, Fig. 25, that is formed from the blank of Fig. 24. This blank has a number of U-shaped cuts 96 the open ends of which are joined by score lines 97 to provide tongues 98 that are turned up as shown in Fig. 25. A wing 99 adjoins one side along a score line 100 and is turned up as shown in Fig. 25. The width of this wing substantially equals the height of tongues 98 and it may serve as a tag that bears the name of the articles in the package, the manufacturer's name or trade mark, or other indicia.

In Figs. 26 and 27, I show a sealed package of biscuit using the holder and deck of Figs. 23 and 25. Four stacks of biscuit, each three high, are placed on the bottom 84 of the holder. The deck is then placed on these stacks and four more stacks of biscuit placed on it, sufficient to bring the top biscuit level with the tops of tongues 98, and the top of the back 90. The lips 87, 88 are then turned in and the whole wrapped and sealed in a transparent wrapper, as heretofore described.

From the foregoing it will be seen that my invention contemplates many modifications and variations and I claim all such that come within the scope or intent of my claims.

All of the decks shown are adapted for use with both forms of holder and variations thereof. The tongues shown on some of the decks may have a height equal to one, two or more biscuit, depending upon several variables, such as size and style of the package, and thickness and number of biscuit.

The wings 54, 55 and 99 may be plain or ornamented in any desired manner, or they may bear any suitable indicia, such as the name of the articles in the package, manufacturer's name or trade mark, selling price, etc.

The holders and decks may be made from any suitable material, but for packaging biscuit and other food products, I prefer to use a cheap board, such as cracker-shell board, that has been coated with lacquer, plasticized gelatin, or other substance to make it grease-resistant. For some articles, I make the holders from patent coated news board with the white or coated side on the outside. The white outside may be left plain or be decorated in any suitable manner. The inside "news" surface, with which the articles come in contact, may be coated with a grease-proof compound, as water soluble methyl cellulose plasticized with glycerine. The decks usually are made from plain board, as cracker-shell, and are grease-proofed on both surfaces.

The wrapper preferably is cellophane or other transparent material that is moisture-proof and can be heat sealed. This makes the entire package both grease-resistant and moisture-proof, which contributes to a greatly lengthened shelf life of the contents. The sealed ends of the wrapper may be covered with an ornamental seal or left plain as illustrated.

The holder and deck, when filled with biscuit and tightly wrapped, form a strong rigid package that gives ample protection to the contents and prevents breaking and "crumbing" as is inevitable with cellophane bags. The packages are neat in appearance, hold the biscuit firmly in neatly stacked relation and afford adequate display thereof.

The packages are adapted to bundling for shipment and handling, thereby saving the cost of shipping containers. When bundled, the top and bottom packages are placed or stacked with their top faces inward, so that only the ends and bottoms are exposed to shock. The packages forming the bundle, usually six or twelve, are then wrapped and sealed in a heavy paper wrapper, as is now common practice with cartons.

With some types of biscuit, for example, rectangular ones as shown in Fig. 5, and other articles, the deck is not needed to make a sturdy package. The holder with its upturned ends and overlying lips gives ample protection when tightly wrapped.

I have shown and described my package as adapted for biscuit, but this is only by way of illustration. It is to be understood, therefore, that the term "biscuit" is not a limitation on the invention, but is indicative of and includes all products that may be contained in my improved package.

Having thus described and illustrated my invention, what I claim is:

1. A package for articles arranged in a plurality of stacks comprising a holder open on two sides and having a rectangular bottom on which the stacks of articles are placed, an end at each end of the bottom extending upward to the tops of the stacks of articles, each end having a resilient lip overlying the adjacent stacks of articles, a deck

of substantially the same size as said bottom arranged parallel thereto and between articles in the stacks, said deck forming a brace between said ends and having tongues extending upward between the stacks, and a transparent wrapper enclosing the holder, deck, and articles and being supported by said tongues and sealed against the ends and bottom of the holder, the resilient lips at the ends of said holder exercising themselves to press against the wrapper to hold it under tension and maintain its surface rigidity and preserve the rectangular shape of the package.

2. A package for articles arranged in a plurality of stacks comprising a holder open on two sides and having a rectangular bottom on which the stacks of articles are placed, an end at each end of the bottom extending upward to the tops of the stacks of articles, each end having a resilient lip overlying the adjacent stacks of articles, a deck of substantially the same size as said bottom arranged parallel thereto and between articles in the stacks, said deck forming a brace between said ends and having a wing at one edge extending upward substantially to the tops of the stacks, and a transparent wrapper enclosing the holder, deck, and articles and sealed against the ends and bottom of the holder.

3. A package for articles arranged in a plurality of stacks comprising a holder open on two sides and having a rectangular bottom on which the stacks of articles are placed, an end at each end of the bottom extending upward to the tops of the stacks of articles, each end having a resilient lip overlying the adjacent stacks of articles, a separator of substantially the same size as said bottom arranged parallel thereto and between articles in the stacks, said separator bracing said ends and having tongues extending upward between the stacks and a wing extending upward from one edge, the tops of said tongues and wing being substantially in the plane of said resilient lips, and a transparent wrapper enclosing the holder, separator, and articles and sealed against the ends and bottom of the holder.

4. A package for articles arranged in a plurality of stacks comprising a holder open on two sides and having a rectangular bottom on which the stacks of articles are placed, an end at each end of the bottom extending upward to the tops of the stacks of articles, each end having a resilient lip overlying the adjacent stacks of articles, a deck of substantially the same size as said bottom arranged parallel thereto and between articles in the stacks, said deck forming a brace between said ends, tongues extending above the deck and between the stacks of articles, said tongues extending substantially to the tops of the stacks, and a transparent wrapper enclosing the holder, deck, and articles and being supported by said tongues and sealed against the ends and bottom of the holder, the resilient lips at the ends of said holder exercising themselves to press against the wrapper to hold it under tension and maintain its surface rigidity and preserve the rectangular shape of the package.

5. A package for articles arranged in a plurality of stacks comprising a holder open on two sides and having a rectangular bottom on which the stacks of articles are placed, an end at each end of the bottom extending upward to the tops of the stacks of articles, each end having a resilient lip overlying the adjacent stacks of articles, a deck of substantially the same size as said bottom arranged parallel thereto and between articles in the stacks, a U-shaped divider having a base

resting on the holder bottom and adapted to hold at least one stack of articles between its upwardly extending legs, the tops of the legs extending above the deck and providing tongues between stacks of the articles, and a transparent wrapper enclosing the holder, deck, and articles and sealed against the ends and bottom of the holder.

6. A package for articles arranged in a plurality of stacks comprising a holder, a deck and a transparent wrapper, said holder having a bottom, a back and two ends and being open on the top and one side, the holder ends being of the same height as the back and each having a resilient lip turned inward over the open top, the deck being of the same size as the holder bottom and dividing the stacks of articles into upper and lower portions, the wrapper tightly enclosing the holder, deck and articles and being sealed against the bottom and ends of the holder.

7. A package for articles arranged in a plurality of stacks comprising a holder, a deck and a transparent wrapper, said holder having a bottom, a back and two ends and being open on the top and one side, the holder ends being of the same height as the back and each having a resilient lip turned inward over the open top, the back of the holder having a number of cut-outs corresponding to the number of stacks of articles, the deck being of the same size as the holder bottom and dividing the stacks of articles into upper and lower portions, the wrapper tightly enclosing the holder, deck and articles and being sealed against the bottom and ends of the holder.

8. A package for articles arranged in a plurality of stacks comprising a holder, a deck and a transparent wrapper, said holder having a bottom, a back and two ends and being open on the top and one side, the holder ends being of the same height as the back and each having a resilient lip turned inward over the open top, the deck being of the same size as the holder bottom and dividing the stacks of articles into upper and lower portions, the deck having an upstanding wing at its front edge extending to the same height as the top edges of the ends and back, the wrapper tightly enclosing the holder, deck and articles and being sealed against the bottom and ends of the holder.

9. A package adapted to contain and display a plurality of stacks of articles comprising a holder open on two sides and having a rectangular bottom on which the stacks rest, an end extending upwardly at each end of the bottom to the top of the stacks, resilient lips extending from the tops

of the ends toward each other and over marginal portions of their adjacent stacks, a deck extending between said ends parallel to the bottom of the holder and holding a minor portion of said stacks, said deck engaging said ends near the lips and bracing them against inward movement, and a transparent heat sealed wrapper completely and closely enclosing said holder, deck and stacks of articles, whereby the wrapper prevents lateral movement of the stacks of articles and the deck holds the top articles in the stack closely adjacent the wrapper for effectual display thereof.

10. A package for articles arranged in a plurality of stacks comprising a holder open on two sides and having a rectangular bottom on which the stacks of articles are placed, an end at each end of the bottom extending upward to the tops of the stacks of articles, each end having a resilient lip extending over the adjacent stacks of articles, a deck of substantially the same size as said bottom arranged parallel thereto and between articles in the stacks, said deck bracing the ends against inward movement, a transparent wrapper enclosing the holder, deck and articles and sealed against the ends and bottom of the holder, said wrapper restraining the articles and deck against lateral movement on the holder and said resilient lips exercising themselves to press against the wrapper to hold it under tension and maintain its surface rigidity and preserve the rectangular shape of the package.

GEORGE ARLINGTON MOORE.
